GRINDING MILL

Martin M. Spanel, Flint, Mich.

Application December 9, 1943, Serial No. 513,502

3 Claims. (Cl. 241—103)

This invention relates to a grinding mill designed primarily for the grinding of paint, and the invention has for its primary object the provision of a mill of this kind which is so constructed as to provide for expeditious and economical grinding of paint in a thoroughly satisfactory manner.

More specifically, objects of the invention are to provide a grinding mill which is simple in construction, durable, compact, thoroughly efficient in use, conveniently operated, and inexpensive to manufacture and assemble.

Specific objects and features of the invention will become apparent from the following description when considered in connection with the accompanying drawings, and the invention consists in the novel form, combination and arrangement of parts hereinafter more fully described, shown in said drawings and claimed.

In the drawings, wherein like reference characters indicate corresponding parts throughout the several views:

Figure 1 is a front elevational view of a horizontal type of grinding mill constructed in accordance with the present invention.

Figure 2 is a central vertical sectional view thereof taken on line 2—2 of Figure 1.

Figure 3 is a fragmentary detail section taken on line 3—3 of Figure 2.

Figure 4 is a fragmentary enlarged elevational view looking toward the left of Figure 2.

Figure 5 is a view similar to Figure 2, of a vertical type of grinding mill constructed in accordance with the present invention.

Figure 6 is a top plan view thereof with the reducing gearing omitted.

Figure 7 is a horizontal section taken on line 7—7 of Figure 5, and

Figure 8 is a fragmentary detail section through the casing, taken on the plane of line 8—8 of Figure 5, and showing the drain outlet for the ground material.

Referring more in detail to the drawings, the present grinding mill includes a casing having a circular wall 5 of frusto-conical form, enclosed at its smaller end by a wall 6 whose inner surface of its marginal or outer portion is of conical form and disposed at right angles to the surface of the wall 5, as at 7. At the lowermost part of the casing, the latter is provided with an outlet opening 8 for draining or discharging the ground material therefrom, and associated with this opening is a manually openable closure gate 9. A discharge spout 10 is provided on the casing outwardly of the opening 8 to properly cause the

discharged ground material to flow into a collection receptacle.

Journaled centrally of the end wall 6 is a shaft 11 having a squared inner end 12 projecting into the adjacent end of the casing and having secured thereon the hub 13 of a carrier embodying a circular series of channel-shaped holder arms 14 that project in diverging relation from the hub 13 toward the opposite end of the casing, or the larger end of the latter. At the inner sides of the holder arms and at their inner portions, said arms are provided with longitudinal vanes 15, whereby the carrier may act as a stirrer for thoroughly mixing the material to be ground as said carrier is rotated during the grinding operation. The holder arms 14 are of semi-circular contour, and loosely and revolvably mounted in each holder arm in position to engage the inner surface of the casing wall 5 is a cylinder grinding roll 16, which may be in one piece or in a plurality of transverse sections, as desired. The single or one-piece type of roll is illustrated in Figure 2, and the sectional type of roll is shown in Figure 5. As shown clearly in Figures 2, 5 and 6, each holder preferably has a liner 17 of smooth wear-resisting material.

A suitable packing means is provided at 17 to prevent leakage of material from the casing about the shaft 11 where the latter extends through the wall 6, and on the outside of said wall there is provided a gear casing 18. This casing is preferably of grease-tight construction to house gearing between the shaft 11 and a drive shaft projecting into said housing 18 transversely of shaft 11. This gearing may include a large bevel gear 19 secured on shaft 11 within the housing 18.

In Figures 1 to 4, inclusive, there is shown a horizontal type of grinding mill embodying the present invention, wherein the larger end of the casing is closed by a removable wall 20 provided in its lower portion with the outlet opening 8 and having at its upper portion an open top feed hopper 21 provided with a top closure 22 and adapted to facilitate the introduction of the material to be ground to the casing. In this embodiment, the wall 5 is shown as having a water jacket 23 provided with pipe connections 24 and 25 to facilitate the circulation of water therethrough and thereby acting to cool the wall 5 and rollers 16 during the grinding operation.

Means is provided to impart slight longitudinal adjustment of the shaft 11 and to thereby cause corresponding adjustment of the carrier relative to the casing so as to vary the degree of pressure with which the rolls 16 contact the wall 5.

Due to the conical form of wall 5 and the diverging relation of rolls 16, only slight adjustment of this kind is needed to secure a decided variation of pressure and thereby control the fineness of grinding. This adjusting means, in the form of Figures 1 to 3, inclusive, consists in providing a threaded collar 26 on the outer side of gear casing 18 on which is threaded an adjusting wheel 27, the shaft 11 being extended through collar 26 and wheel 27 and having a head 28 on the outer end thereof engaging said wheel 27. Thus, by threading the wheel 27 outwardly, the shaft 11 may be correspondingly moved to draw the carrier in the same direction and to cause the rollers 16 to bear more tightly against the conical wall 5 of the casing. Any suitable means, such as dog 29 arranged to engage teeth or notches 30 of the wheel 27, may be provided for locking the latter in adjusted position.

In Figures 5 to 8, inclusive, there is shown a vertical type of grinding mill embodying the present invention. In this embodiment, the casing wall 5 preferably has a cylindrical extension 31 at the top thereof extending above the rolls 11 and their carrier. Also, the casing is mounted upon a suitable base such as a large cylindrical standard 32 having a large base flange 33. In this embodiment, the shaft 11 depends within the standard 32 and is provided at its lower end with a ball and socket connection 33 with a pivoted arm 34 that extends outwardly through a side of the standard 32 and is pivotally connected to an adjusting screw 35 rotatably mounted on the outside of standard 32. By adjusting screw 35, arm 34 may be swung so as to shift shaft 11 longitudinally and correspondingly move the roll carrier for varying the degree of pressure with which said rolls engage the wall 5 of the casing, thereby varying the fineness of the material being ground. Driving of the shaft 11 in this embodiment may be accomplished by a bevel gearing 36 within the standard 32 and connecting said shaft 11 with a horizontal shaft 12 extending from a reducing gearing contained in housing 37. As the degree of longitudinal adjustment of shaft 11 necessary to cause the desired variation of grinding is slight, such adjustment of shaft 11 will not interfere with constant meshing of the gearing between shaft 11 and its drive shaft.

Much of the detail construction of both embodiments is similar, and corresponding parts of both forms are indicated by like reference numerals.

In operation, rotary motion is given to shaft 11 so as to rotate the carrier and cause the grinding rolls 16, which bear upon the inner surface of wall 5, to rotate and roll around within the casing. Centrifugal force, assisted by the conical form of the casing and the diverging relation of the rolls, insures contact of the latter with the inner surface of casing wall 5, and the pressure of said contact may be varied by the means described. In this way, the material introduced within the casing will be effectively ground between the surfaces of the rolls and the inner surface of casing wall 5, as well as between the surfaces of the rolls and the linings 17 of holders 14. If desired, the wall 5 may also have a smooth wear-resisting liner, as at 38.

From the foregoing description, it is believed that the construction and operation, as well as

the advantages of the present invention, will be readily understood and appreciated by those skilled in the art. The invention provides a mill which will grind the paint in a thorough efficient manner, and complete drainage of ground material from the casing is provided for. Changes in details of construction are contemplated such as fairly fall within the spirit and scope of the invention as claimed.

What I claim as new is:

1. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms.

2. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms.

3. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms, and means to adjust said shaft longitudinally to correspondingly shift the carrier and thereby vary the degree of pressure with which the rolls engage the inner surface of said circular wall.

4. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms, and means to adjust said shaft longitudinally to correspondingly shift the carrier and thereby vary the degree of pressure with which the rolls engage the inner surface of said circular wall.

5. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms, and means to adjust said shaft longitudinally to correspondingly shift the carrier and thereby vary the degree of pressure with which the rolls engage the inner surface of said circular wall.

6. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms, and means to adjust said shaft longitudinally to correspondingly shift the carrier and thereby vary the degree of pressure with which the rolls engage the inner surface of said circular wall.

7. A grinding machine comprising a casing having a circular wall of frusto-conical form and provided with a wall for closing the smaller end thereof, the last-mentioned wall having a conical marginal inner surface portion extending at right angles to the inner surface of said circular wall, a shaft journaled centrally in the end wall and having an end projecting into the adjacent end of the casing, a carrier including a hub fixed on the inner end of said shaft within the casing and including carrier arms projecting from the hub in diverging relation toward the other end of the casing, said arms comprising semi-circular channel members, cylindrical grinding rolls rotatably fitting in said arms in position to contact and roll upon the inner surface of said circular wall of the casing, and longitudinal mixing blades on the inner sides of said holder arms, said casing having a discharge opening and a closure therefor.

MARTIN M. SPANEL.
